RADIO-FREQUENCY ELECTRICAL HEATING EQUIPMENT

Edmund C. Stanley, Wokingham, England, assignor to Radio Heaters Limited, Wokingham, England, a British company

Application December 1, 1947, Serial No. 789,062
In Great Britain January 6, 1947

6 Claims. (Cl. 219—47)

1

This invention relates to high frequency electrical heating equipment of the dielectric heater type in which the articles to be heated are placed in a heating chamber between the two heating electrodes.

In such apparatus, it is the usual practice to hinge the lid about an axis towards the back of the oven casing so that the lid is opened by being swung upwards. The upper electrode is generally arranged to be lifted with the lid to allow the charge to be removed from the heating chamber with the minimum difficulty and obstruction.

It is usual to work with an air gap between the upper electrode and the charge to be heated so as to avoid contact between that electrode and the charge. A parallelogram linkage is generally provided to raise and lower the upper electrode while maintaining the face of the latter parallel with the face of the lower electrode while the lid is closed and the air gap is adjustably by means of a screw brought out through the lid of the oven. This mechanism is easily arranged so long as the upper electrode is connected to earth and the lower electrode is operated as the live electrode. However, it is sometimes convenient to have the upper electrode live with the lower electrode earthed or with some oscillator circuits, to have both electrodes live. Hitherto, in such cases, a flexible conductor has been provided to convey the radio-frequency current to the upper live electrode and the heating chamber has been of considerably increased height resulting from the fact that a parallelogram linkage is employed and the live electrode is carried on insulators projecting down from the forward end of the parallelogram linkage.

The object of the present invention is to avoid the necessity of employing a flexible conductor which is a source of trouble and to allow the height between the lower surface of the movable upper electrode and the parallelogram linkage to be considerably reduced.

According to the invention, a parallelogram linkage is employed and is arranged so that the lower longer member serves as the connection bringing in the radio frequency current from the high frequency generator to the upper electrode while the upper longer member of the parallelogram is maintained at earth potential. The short vertical link at the front end connecting the upper and lower members consists of an insulator. By keeping the upper parallelogram member at earth potential, the mechanism for adjusting the air gap below the live upper electrode is greatly

2

simplified and may consist of a screwed rod operated by a knob on the top of the lid so that adjustment can be effected without opening the lid.

5 In order that the invention may be clearly understood and readily carried into effect, some forms of the novel arrangement will now be described, by way of example, with reference to the accompanying drawings in which:

10 Figure 1 is a central vertical section of one form of heating apparatus taken at right angles to the axis of the hinge of the cover;

Figure 2 is a vertical section at right angles to Figure 1 on the line II—II in Figure 1; while

15 Figure 3 is a circuit diagram showing a suitable simple generator circuit;

Figure 4 is a central vertical section of a modified and simple form of apparatus; and

20 Figure 5 is a sectional plan of the apparatus shown in Figure 4 taken on the line V—V in that figure.

Referring to Figures 1 and 2, the hinged cover 1 is pivoted to the fixed casing 2 about a spindle 3. This spindle at each end is supported in two strips 4, 5 riveted to the inside of the side wall 6 of the casing 2 at the points 7. It is prevented from axial movement by washers 8 and pins 9 passing through the spindle 3. The strip 5 is turned over at the top at 10 and is braced to the

25 strip 4 by a bolt 11 and nut 12. The spindle 3 at each end also passes through an inclined strip 13 riveted at the points 14 to the inside of the side walls of the cover or lid 1 so that the lid 1 can be turned upwardly about the spindle 3. When

30 closed down, the lid 1 is retained by a catch 1a slidable on two guide rods 2a in the casing 2. The material to be heated is placed on the lower stationary electrode 15 and the upper movable electrode is shown at 16. The lower member of

35 the parallelogram consists of a pair of parallel arms 17 pivoted at the back about a pin 18, whose axis is at a lower level than that of the hinge spindle 3. The upper parallelogram member consists of a single plate 19 of a downwardly-

40 turned channel section and pivoted at its rear end to the framework of the lid 1 about a pin 20 which is supported at a level above that of the hinge 3 in the side members of a bracket 21 secured to a plate 22 fixed in the upper part of the lid 1 so that

45 the pivot pin 20 is swung backwards when the lid 1 is raised. The upper movable electrode 16 is fixed to the bottom of an insulator 25 which forms the front link of the parallelogram since the lower arms 17 are pivoted at their front ends 50 at the points 26 to brackets 27 carried by the

electrode 16, while the upper parallelogram member 19 is pivoted at its front end on a pin 28 mounted in a bracket 29 fixed at the top of the insulator 25.

The lower arms 17 at their rear ends have the pivot formed by a heavy transverse pin 18 fixed by screws 30 to a horizontal plate 31 fixed to the outlet terminal 32 which extends through the top of an insulator 33 fixed at the back of the oven to the base plate 34. The live high frequency current connection to the upper electrode 16 passes in through the pillar 35 to the terminal 32 and through the arms 17 and brackets 27 to the electrode 16. The live electrode system is earthed when the lid 1 is opened by means of a strip 23 bearing at its upper end at 23a against the plate 22 fixed to the lid. When the lid 1 is raised, the strip 23 is swung out by the action of a coiled loading spring 23b surrounding the pivot pin 23c; consequently the strip 23 comes into contact with the pivot pin 18 which is thereby earthed. When the lid 1 is closed down, the plate 22 exerts a thrust on the top of the strip 23 at 23a so that the strip is swung away from the pivot pin 18 into the position shown in Figure 1.

The gap between the electrodes 15, 16 is arranged to be adjusted when the lid 1 is closed down by rotating a knob 36 pinned to a screwed rod 37 having a bearing in the top of the lid 1 so that the rod 37 is prevented from moving axially. The rod 37 is threaded into a nut 38 which can turn on the ends of screws 39 secured in L-shaped brackets 40 fixed to a channel-section arm 41 on which the upper parallelogram member 19 rests and which is pivoted about the same axis 20 as the member 19. This arrangement enables the adjustment to remain set and undisturbed when the lid 1 and upper electrode 16 are swung upwards. When this happens, the pivot pin 20 as already mentioned is swung backwards, the insulator 25 tilted and the upper electrode raised so as to expose its under surface for cleaning. If a layer of material to be heated which is too thick is placed on the lower electrode 15, the upper electrode 16 and the upper parallelogram member 19 which is connected to it by the insulator 25 are free to ride up slightly while the lid 1 is closed down without straining any of the joints.

In Figure 3 is shown a simple form of conventional radio-frequency generator circuit, the electrode 16 and arms 17 being shown diagrammatically. The oscillator tube 42 is a triode with grid coils 43, 44 in series respectively with a resistor 45 and condenser 46. The tank coil 47 and condenser 48 are connected between the anode 49 of the tube 42 and the filament cathode 50 which is earthed at 51 while the high tension supply is connected to the anode 49 through the anode choke coil 52. The output coil 53 is coupled to the tank coil 47 and is connected to the upper electrode 16 through the lower parallelogram members 17.

In the modified form shown in Figures 4 and 5, the lower earthed electrode 15 is again supported on the oven base plate 34 and the upper live electrode 16 carries a stirrup-shaped bracket 54 on the top of which is mounted the insulator 25. The electrode 16 is suspended on two flat strips 17, 19 forming the lower and upper longer members of the parallelogram linkage and pivoted respectively at 26 and 28 to the electrode 16 and the top of the insulator 25. The lower strip 17 conducts the current to the live

electrode 16 from the outlet terminal 32 at the end of the pillar 35 which, in this instance, extends horizontally through the insulator. The strip 17 is pivoted at its rear end at 18 on a plate 31 carried by the insulator 33 while the strip 19 is pivoted at 20 on a channel-shaped bracket 55. The bracket 55 is in turn pivoted to a pair of brackets 56 fixed to the wall of the oven casting 2, the pivot being formed by a pair of pins 57 providing a pivoted axis in alignment with that of the hinge pin 20.

For raising and lowering the upper electrode 16, a mechanism is provided comprising a knob 36 fixed to a threaded spindle 37 engaging within a tapped boss 58 fixed to the end of a transverse bar 59 which passes through the side plates of the bracket 55 and engages below the bar 59. The spindle 37 is journalled and guided in a bush 60 in the top wall of the oven so as to be prevented from axial movement as in Figures 1 and 2 and when rotated, raises or lowers the bar 59 so as to raise or lower the upper electrode 16. As before, the electrode is free to rise or float since the strip 19 is resting on the bar 59. A knurled nut 61 is provided to lock the spindle 37 in any desired position.

I claim:

1. In a high frequency dielectric heater, a stationary electrode, a parallelogram linkage having its members located in a plane at a right angle to the surface of said electrode and consisting of two longer members pivotally mounted on fixed pivots and an insulating link connecting the movable ends of said longer members, an adjustable electrode rigidly connected to said insulating link and mounted with its face parallel to the face of said stationary electrode and electrically connected to the movable end of said longer parallelogram member which is nearer to said stationary electrode and a ground connection for the other of said longer parallelogram members.

2. In a high frequency dielectric heater, a metallic oven casing, a cover hingedly mounted thereon, a stationary horizontal electrode mounted in said oven casing, a parallelogram linkage having its members located in a vertical plane above said electrode and consisting of upper and lower longer members and a movable insulating link pivotally connected to the movable ends of said longer members, said lower longer parallelogram member being pivotally mounted on said casing and insulated therefrom and said upper parallelogram member being pivotally mounted on said cover and grounded thereto and an adjustable horizontal electrode spaced from said stationary electrode and rigidly connected to the lower end of said insulating link and electrically connected to the movable end of said lower longer parallelogram member.

3. In a high frequency dielectric heater, a metallic oven casing, a cover hingedly mounted thereon, a stationary horizontal electrode mounted in said oven casing, a parallelogram linkage having its members located in a vertical plane above said electrode and consisting of upper and lower longer members and a movable insulating link pivotally connected to the movable ends of said longer members, said lower longer parallelogram member being pivotally mounted on said casing and insulated therefrom and said upper parallelogram member being pivotally mounted on said cover and grounded thereto, an adjustable horizontal electrode spaced from said stationary electrode and rigidly connected to the lower end of said insulating link and electrically connected

to the movable end of said lower longer parallelogram member, and means mounted in said cover for adjusting the relative angular position of adjacent members of said parallelogram linkage in a vertical plane.

4. In a high frequency dielectric heater, a metallic oven casing, a cover hingedly mounted thereon, a stationary horizontal electrode mounted in said oven casing, a parallelogram linkage having its members located in a vertical plane above said electrode and consisting of upper and lower longer members and a movable insulating link pivotally connected to the movable ends of said longer members, said lower longer parallelogram member being pivotally mounted on said casing and insulated therefrom and said upper parallelogram member being pivotally mounted on said cover and grounded thereto, an adjustable horizontal electrode spaced from said stationary electrode and rigidly connected to the lower end of said insulating link and electrically connected to the movable end of said lower longer parallelogram member and a threaded rod rotatably journaled in said cover and having threaded engagement with said upper parallelogram arm so as to lift same on being rotated.

5. In a high frequency dielectric heater, a metallic oven casing, a cover hingedly mounted thereon, a stationary horizontal electrode mounted on said oven casing, a parallelogram linkage having its members located in a vertical plane above said electrode and consisting of upper and lower longer members and a movable insulating link pivotally connected to the movable ends of said longer members, said lower longer parallelogram member being pivotally mounted on said casing and insulated therefrom and said upper parallelogram member being pivotally mounted on said cover and grounded thereto, an adjustable horizontal electrode spaced from said stationary electrode and rigidly connected to the lower end of said insulating link and electrically connected to the movable end of said lower longer parallelogram member, a support engaging below said upper parallelogram arm and pivotally

mounted about an axis substantially in alignment with the pivotal axis of said upper parallelogram arm and a threaded rod rotatably journaled in said cover and having threaded engagement with said support so as to lower and lift same on being rotated.

6. In a high frequency dielectric heater, the combination of a metallic casing, a stationary horizontal electrode mounted in said casing and being electrically connected thereto, a parallelogram linkage arranged within said casing and having its parallel arms arranged in a vertical plane, the upper arm of said linkage being pivotally connected at one end to said casing, and the other arm of said linkage being pivotally connected at one end to an insulating member carried by said casing, a link element pivotally connected to the movable ends of said arms, a movable electrode rigidly connected to said link element and being electrically connected to the lower arm of said linkage, means connected between said casing and the upper arm of said linkage for adjusting said linkage in a vertical plane to vary the separation between said electrodes, at least one element of said linkage interposed between said last named means and said movable electrode being formed of insulating material, and means electrically connecting the pivoted end of said lower arm to an insulated supply terminal carried by said casing.
